FOLDABLE STANDARD BASE STRUCTURE

Leo J. Du Mais, Chicago, Ill., assignor to Da-Lite Screen Company, Inc., Chicago, Ill., a corporation of Illinois

Application August 31, 1954, Serial No. 453,289

3 Claims. (Cl. 248—171)

This invention relates to screen stands and analogous structures of the kind which comprises an upright standard and a supporting base structure, comprising a plurality of legs of tripod or other foldable form, which legs are hinged to the standard in such manner as to be spread apart for supporting the standard and to be collapsible to lie in compact position along the standard.

The main objects of the invention are to provide improvements in portable projection screen stands whereby the supporting tripod base legs are so connected together and to the standard that the spreading and collapsing of the legs will be in some respects automatic so as to require a minimum of handling by the user in the acts of setting up and taking down the standard; and to provide improved latching means for the tripod legs that operates in an improved fashion to hold the legs in their collapsed position for storage and that is readily unlatched by manipulation of the standard with one of the legs in contact with the floor and wherein, upon such unlatching the legs by downward pressure and tilting of the standard, the legs will be automatically spread apart by spring recoil and gravity upon being lifted from the floor.

An illustrative specific embodiment of this invention is shown in the accompanying drawings, in which:

Figure 1 shows the standard with its legs in collapsed position and tilted to an initial position for causing the legs to spread apart.

Fig. 2 is a perspective view of the standard with its legs spread apart for supporting the standard upright on a horizontal floor.

Fig. 3 is a longitudinal section of the standard with its legs latched in collapsed position and showing the structure of the leg mounting brackets and latch mechanism.

Fig. 4 is a transverse section of the same taken on the line 4—4 of Fig. 3.

Fig. 5 is a transverse section of the tubular standard taken on the line 5—5 of Fig. 3.

In the form shown, the standard 10 is a tubular bar equipped with tripod legs 11 which are foldable to a collapsed position, as illustrated in Fig. 1, for compact storage when it is out of use. It is adapted to have its legs spread apart for supporting the standard 10 in an upright position.

The standard 10, as illustrated in the drawings is preferably of rectangular cross section and has an upper bracket member 12 that is longitudinally slidable on the standard 10, a lower bracket member 13 which is also longitudinally slidable on the standard but to a more limited extent, and an intermediate bracket member 14 which is fixed to the standard. Each of the bracket members has wing-like lugs directed radially outward from the axis of the standard and each lying within the plane of movement of a respective leg when such leg is shifted between its expanded and collapsed positions.

The upper ends of the legs 11 are pivoted at 15 to the lugs 16 of the upper bracket member. Spreader links 17 are pivotally connected at 18 to the lugs 19 of the lower

2

bracket and their outer or upper ends are pivoted by pins 20 on the leg 11 in position to engage latch hooks on the intermediate bracket member 14.

As shown in Figs. 2 and 3, the bracket members 12 and 13 are of identical form, but one is inverted with respect to the other in their positions on the standard.

The intermediate bracket member 14 is similar in structural make-up except that, instead of having merely circular bores in its wing lugs for the reception of pivot pins, it has a slot 22 inclined downwardly and inwardly from the outer end of the lug so that the inner end of the slot 22 will serve as a seat for the pivot pin 20 and its sides will serve as cam surfaces 24 and 25 adapted to guide the pin 20 into and out of such seat. The lower portion of each wing lug of bracket 14 forms a latch hook 23 that partly embraces such pivot pin 20. The pivot pin 20, in addition to connecting the spreader link to its leg, has the extra function of serving as a keeper coacting with the latch hook 23 to hold the respective leg in its collapsed position, as clearly shown in Fig. 3. The bracket 14 is fixed on the standard 10, as by a set screw 26 or otherwise as may be desirable to conform to local conditions on the standard.

For convenience of manufacture, the legs 11 are of inverted channel-form in section and the spreader bars 17 are also of channel form so that these bars nest one within another, as shown at the left of Fig. 3, when the respective leg is in its collapsed position.

The lower bracket member 13 is connected to the standard 10 by a cross pin 27 which extends through a pair of slots 28 in the opposite walls of the tube 10 and its ends are fast in the lower bracket member 13 which thus has a limited range of sliding movement along the tube 10, which movement is limited by the ends of slots 28.

A compression spring 29 bears between the cross pin 27 of the bracket member 13 and a cross pin 30 within the tube 10, so that this spring 29 normally tends to urge the bracket member 13 downwardly along the tube 10 and acting through the link 17, normally holds the keeper and pivot pin 20 in position for latching engagement with the hook 23 to hold the legs in their retracted or collapsed position along the tube 10, as shown in Fig. 3.

The three bracket members are of identical construction except for the fact that the slots 22 in the wing lugs of the bracket member 14 are modified by having the slot 22 extend from the pivot bore outward to the end of the lug, as hereinbefore described. Preferably, these bracket members are each made up of three straps that

form segments of a band around the standard 10 with wing portions projecting from this band to form the wing lugs which serve as hinge members. The hole 27.1 of bracket 12 may serve to permit the attachment of a fingerhold (not shown) to be attached to bracket 12 if desired.

In the operation of spreading the legs to set up the standard, the operator holds the tube 10 in an inclined position with one of its legs bearing on the floor in about the disposition shown in Fig. 1. The legs are equipped with rubber cups 31 which will not mar a smooth surface or tear a carpet. While only one of the legs is in contact with the floor, as shown, the operator presses the standard downward and rocks it away from the point of contact with the floor as indicated by arrow 32, compressing the spring 29 of that leg against the cross pin 27. The latch hooks 23, being fast on the standard 10, thus move downward with respect to the keepers 20 on the legs 11, whereupon cam surfaces 25 of the slot 22, coacting with the keeper pins 20, cause the legs to spread apart and free the keepers 20 from the hooks 23.

After the legs have spread apart sufficiently to free

the keepers 20 from the latch hooks 23, the bracket member 12, due to its weight and that of the parts connected thereto, falls by gravity until it is stopped by the bracket member 14 with the legs fully spread apart, as shown in Fig. 2, and the device is ready to be set upright on the floor.

To collapse the legs, it is merely necessary for the operator to slide the bracket member 12 upward along the tube 10 to cause the links 17 to swing inward until the keepers 20 ride up on the cam surfaces 24 and snap over the hooks 23 into their latching position, due to the normal urge of the spring 29.

Although but one specific embodiment of this invention is herein shown and described, it will be understood that numerous details of the construction shown may be altered or omitted without departing from the spirit of the invention as defined by the following claims.

I claim:

1. In a stand of the class described, a standard, an upper bracket member slidable along said standard, supporting legs for the standard pivoted on said upper bracket member to swing in radial planes between spread apart and collapsed positions, a lower bracket member slidable on said standard, coacting means on the standard and lower bracket for limiting the movement of the bracket on the standard, spreader links pivoted at their lower ends to said lower bracket member and at their upper ends to respective said legs and adapted to swing said legs outward from said standard when said upper bracket member is shifted downward along said standard and to swing said legs inward toward said standard when said upper bracket member is shifted upward along said standard, a rigid intermediate bracket member fixed on said standard having upwardly-opening latch hooks thereon individually extending radially therefrom in the paths of movement of respective legs with respect to the standard, keeper means on said legs intermediate their ends adapted to be engaged by said latch hooks when the legs are in their collapsed position, and spring means acting between said standard and said lower bracket member to urge the lower bracket downwardly on the standard to hold said keeper means normally in position for engagement with said latch hooks and adapted to yield through the relative movement of said standard and said lower bracket member to release said keeper means from said latch hooks.

2. In a stand of the class described, a standard, an

upper bracket member slidable along said standard, supporting legs for the standard pivoted on said upper bracket member to swing in radial planes between spread apart and collapsed positions, a lower bracket member slidable on said standard, coacting means on the standard and lower bracket for limiting the movement of the bracket on the standard, spreader links pivoted at their lower ends to said lower bracket member and at their upper ends to respective said legs and adapted to swing said legs outward from said standard when said upper bracket member is shifted downward along said standard and to swing said legs inward toward said standard when said upper bracket member is shifted upward along said standard, a rigid intermediate bracket member fixed on said standard having upwardly-opening latch hooks thereon individually extending radially therefrom in the paths of movement of respective legs with respect to the standard, keeper means on said legs intermediate their ends adapted to be engaged by said latch hooks when the legs are in their collapsed position, and spring means acting between said standard and said lower bracket member to urge the lower bracket downwardly on the standard to hold said keeper means normally in position for engagement with said latch hooks and adapted to yield through the relative movement of said standard and said lower bracket member to release said keeper means from said latch hooks coacting with said keeper means to force said legs apart through further relative movement of said standard and lower bracket member.

3. A stand structure according to claim 2 in which the spreader links are pivoted by pins at their lower ends to said lower bracket member and by pivot pins at their upper ends to respective said legs and the keeper means are the same pivot pins that connect the links to the legs.
